EXTRACTION PROCESS

Le Roi E. Hutchings, Crystal Lake, and William A. Krewer, Arlington Heights, Ill., and Nathaniel L. Remes, Miami, Fla., assignors to The Pure Oil Company, Chicago, Ill., a corporation of Ohio

Filed Dec. 3, 1957, Ser. No. 700,475

6 Claims. (Cl. 260—674)

This invention relates to a process for the separation or extraction of aromatic hydrocarbons from hydrocarbon mixtures, including paraffinic hydrocarbon mixtures, and, more particularly, to an extraction process using dimethyl ammonium dimethyl carbamate with certain critical amounts of water in order to attain high-purity extracts during said process.

Aromatics such as benzene and alkyl-substituted homologues are present in many hydrocarbon mixtures. Aromatics are present in lubricating oil fractions. Benzene is present in coal tar fractions. Liquid-phase extraction of hydrocarbon mixtures of these types with selective solvents, at a temperature substantially below the point at which the solvent is completely miscible with the mixtures, constitutes one known method of separating or refining the aromatic content thereof. Although such processes produce an extract which is relatively rich in aromatics and a raffinate relatively rich in paraffinic hydrocarbons, the separation is only partial and yields fractions containing substantial quantities of undesirable constituents. It is often highly desirable that the purity of the extract phase be high, e.g., in the production of nitration-grade benzene, purities of 99.5% or higher are sought. It is well accepted in the art that the presence of an anti-solvent, such as water or other highly polar compounds, may in some instances aid phase separation, improve product purity, etc., but in other instances much better results are obtained by using the selective solvent or solvent mixture alone in substantially anhydrous condition. No set rule has so far been established on which one can rely to predict how a given solvent will act under various conditions or in treating various hydrocarbon mixtures. Furthermore, when an anti-solvent is used, the amount of extract may increase or decrease and product purity fluctuate proportionately. Some anti-solvents increase product purity and decrease the selectivity; others have the opposite effect.

It is also generally recognized in the solvent extraction art that substantially pure extract cannot be produced by extraction alone if the extract phase of the mixture being treated is completely miscible with the solvent. Here again the use of anti-solvents, including water, with the principal solvent has been employed to overcome this miscibility to a certain extent. However, those processes which employ a solvent to remove impurities, such as sulfur compounds or olefins from a hydrocarbon fraction, either do not recognize this fact or use the anti-solvent only to cause phase separation in the extract and thereby recover the solvent. In the extraction processes directed toward separating hydrocarbons of an aro-

2

matic nature from associated mixtures, it is impossible to predict that the water will act satisfactorily as an anti-solvent, and if it does so act, what the effect will be on the extract phase or the overall extraction efficiency.

5 In accordance with this invention, it has been found that the presence of between about 3.0—25.0 volume percent of water at about 60—150° F. increases the selectivity of dimethyl ammonium dimethyl carbamate without affecting the capacity for aromatics, while at the same time 10 avoiding emulsion difficulties and making the process commercially feasible for the preparation of high-purity aromatic products.

The invention herein relates at least in part to the discovery that the type of aromatic hydrocarbon in the 15 feed to be treated, the extraction temperature, the reflux ratios and the degree of purity of the end product make it mandatory that the volume percent or proportion of water present in the solvent during the primary extraction be closely controlled. The discovery may be briefly stated as the finding that there is a direct relationship between the type of aromatic hydrocarbon sought to be isolated in the extract phase, the temperature of extraction and the contact conditions.

20 In general, it has been found that to obtain a predominance of aromatic hydrocarbons of maximum purity in the extract phase or highest selectivity, the amount of water required in the dimethyl ammonium dimethyl carbamate solvent is the least, that is, around 3.0 volume 25 percent, for the xylenes at the lowest extraction temperature of about 80° F. and the greatest, that is, about 25 volume percent, for benzene at the highest practical extraction temperature of about 140° F. The amount of water used may vary from 3.0 volume percent to 25 volume percent as the temperature of the extraction increases, with the result that the extract will predominate 30 in the aromatic homologues of fewer alkyl substituent groups, or the capacity will be greater for the lower molecular weight aromatic homologues present in the feed source. Thus, where the feed source contains a predominance of xylenes, the alkyl-substituted homologues of benzene, or where this type of aromatic is desired to be extracted from a mixture of hydrocarbons,

40 the optimum selectivity and capacity therefor is obtained by using about 3.0 to about 5.0 volume percent of water in the dimethyl ammonium dimethyl carbamate at the lowest extraction temperature of about 80° to 100° F. About 5.0 to 10.0% of water with this solvent produces 45 the optimum selectivity for xylenes at an extraction temperature of about 120° to 140° F. and the optimum selectivity for benzene is found at water concentrations of about 10.0 to 25 volume percent where the extraction 50 temperature varies between about 90° F. to 140° F. For certain types of feeds, as catalytic reformate containing benzene, xylenes and ethyl benzene, the optimum capacity and selectivity are obtained by using water concentrations from about 15.0 to 25.0 volume percent at extraction temperatures of 100° to 120° F.

55 In a specific embodiment of the invention, a high-purity benzene-toluene, xylene concentrate is obtainable from a mixture of fractions of catalytic reformate by solvent extraction with dimethyl ammonium dimethyl-

carbamate with 15.0 to 20.0 volume percent of water at an extraction temperature of about 120° F., using a minimum reflux of about 4.7. Furthermore, if the water content of dimethyl ammonium dimethyl carbamate is increased above 25.0 volume percent, the capacity of the solvent drops to the point where the process is uneconomical and benzene or other aromatics in the solvent begins to force the water out of solution, which results in emulsion difficulties.

Dimethyl ammonium dimethyl carbamate, hereinafter referred to as DADC for simplicity, is a known solvent for impurities in fuel oil and gasoline. DADC is a water-white liquid, boiling at about 140.3° F., having a specific gravity of 1.026, an absolute viscosity at 25° C. of 63.3 cps. and a refractive index at 25° C. of about 1.4512. This solvent has been used to treat a catalytically cracked fuel oil in equal volumes in a single-step extraction at 25° C. with 30 minutes contact, by shaking, allowing the layers to separate, and separately washing with distilled water to produce a raffinate comprising 88% and an extract of impurities comprising 10.9% by volume of the original charge. In such a process the solvent may be suitably separated and recovered by distillation, or alternatively, by washing the phases with water in which the dimethyl ammonium dimethyl carbamate is disclosed as being extremely soluble.

In general, those processes which are adaptable to water dilution to initiate solvent separation from the extract phase are dependent upon a rather steep solubility curve for the solvents in water, and at temperatures of 167° F. or above it is desirable that the solvent be completely miscible with water to effect satisfactory separation and solvent recovery. The use of water in this connection is for the purpose of solvent separation from the extract phase and the high solubility of the solvent in the water mitigates against the presence of water during the extraction process, that is, it promotes emulsification instead of phase separation in the presence of the raffinate. Thus, it is unexpected to find that the presence of 3-25% by volume of water in the solvent during the extraction using dimethyl ammonium dimethyl carbamate avoids emulsification and aids phase separation without undue decrease in capacity, while at the same time increasing the selectivity. Furthermore, it is considered unusual to find that the solvent extraction efficiency can be increased to the point where the purity of the aromatics recovered reaches or exceeds 99.5%.

Accordingly, it becomes a primary object of this invention to provide a process for the separation of aromatic hydrocarbons from hydrocarbon mixtures, employing dimethyl ammonium dimethyl carbamate with certain amounts of water as the selective solvent.

Another object of the invention is to provide a process for the separation of benzene and alkyl derivatives or homologues thereof from hydrocarbon mixtures, employing dimethyl ammonium dimethyl carbamate with certain amounts of water as the selective solvent.

Another object of the invention is to provide a process for the separation of aromatic hydrocarbons from hydrocarbon mixtures by solvent extraction of the hydrocarbon mixtures with dimethyl ammonium dimethyl carbamate containing from about 3.0 to 25.0 volume percent of water, at a temperature from about 80° to 140° F.

A further object of the invention is to provide a process for increasing and maintaining the selectivity of dimethyl ammonium dimethyl carbamate for aromatic hydrocarbons present in admixture with non-aromatic hydrocarbons by employing particular amounts of water in relation to the desired type of aromatic hydrocarbon extracted, the product purity thereof and the process conditions employed, particularly the primary extraction temperature and the reflux ratios.

Another object of the invention is to provide a process for extracting high-purity benzene from benzene-contain-

ing hydrocarbon mixtures, using dimethyl ammonium dimethyl carbamate with certain amounts of water as the solvent.

An object of this invention is to provide a process for extracting high-purity xylenes from hydrocarbon mixtures containing same, using dimethyl ammonium dimethyl carbamate with certain amounts of water as the solvent.

Another object of this invention is to provide a process for extracting a high-purity benzene-toluene-xylene mixture from a concentrate, obtained by blending selected fractions of catalytic reformate by liquid phase selective solvent extraction using dimethyl ammonium dimethyl carbamate with certain amounts of water and a minimum solvent-to-feed ratio of 2/5 with a minimum reflux ratio to charge oil for the extract phase of about 1/4.

A final object of this invention is to provide a process of selective liquid-phase solvent extraction to produce high-purity aromatic hydrocarbons, using from about 15% to 25% by volume of water with the dimethyl ammonium dimethyl carbamate solvent, where the characteristics of the hydrocarbon mixture require operation of the primary extraction stage at a temperature of about 100° to 120° F.

These and further objects of this invention will be explained or become apparent as the description of the invention proceeds.

The attached drawings further illustrate the invention wherein:

Figure 1 is a three-phase diagram of the ternary data obtained using dimethyl ammonium dimethyl carbamate, with less than the necessary amounts of water, in the extraction of benzene.

Figure 2 is a three-phase diagram of ternary data obtained using 12% of water with dimethyl ammonium dimethyl carbamate in the extraction of benzene at 100° F.

Figure 3 is a flow diagram of the general process.

Figure 4 is a three-phase diagram for the system p-xylene-n-heptane-DADC, showing the influence of water.

Before discussing the drawings in detail, a series of experiments are described to show the development of the invention.

EXAMPLE I

In order to demonstrate the effect of the concentration of water in dimethyl ammonium dimethyl carbamate, a feed composition consisting of 45 volume percent of toluene and 55 volume percent of n-heptane was extracted with dimethyl ammonium dimethyl carbamate using different concentrations of water. The volume percent of the toluene recovered in the extract phases produced, and the purity of the toluene therein were determined. A solvent/charge volume ratio of 1/1 and a temperature of 68° F. were used in each run. The results are shown in the following table:

TABLE I
Effect of water concentration on capacity and selectivity of DADC for aromatics @ 68° F.

Run No.	Solvent Composition		Toluene in Extract, Percent Vol. ¹	Extract Toluene Purity, Vol. Percent
	Vol. Percent DADC	Vol. Percent H ₂ O		
1	100	0	50.1	63.5
2	97.6	2.4	46.8	79.7
3	95.7	4.3	40.8	84.5
4	93.9	6.1	35.9	90.0
5	92.2	7.8	31.5	91.3

¹ Percent, by volume, of toluene content of charge.

From the experiments shown in Table I it is apparent

that as the concentration of water is increased, the yield of extract decreases and its purity increases. This means that the water decreases the capacity and increases the selectivity of the dimethyl ammonium dimethyl carbamate at an extraction temperature of 68° F.

It has been found that the minimum requirements of water content in the solvent vary when the solvent mixture is used to extract different hydrocarbons. A series of experiments was conducted in which solutions of n-heptane mixed with various aromatics were treated with dimethyl ammonium dimethyl carbamate, and the water content of the solvent was varied to determine the upper and lower limits of water content that can be used. In conducting these experiments, the upper limit of water concentration was taken as that concentration at which the capacity of the solvent mixture became unsuitably low. The results are shown in the following Table II.

TABLE II

H₂O—Concentrations in DADC to produce substantially pure aromatics @77° F.

Run No.	Ratios of Components ¹ (Parts by Volume) in HC-Mixture Treated				Water Content ² of DADC	
	N-heptane	Benzene	Toluene	Xylene	Lower Limit	Upper Limit
6	1.0	1.0			8.0	16.0
7	1.0		1.0		6.5	10.0
8	1.0			1.0	3.5	6.0
9	4.0	1.0	2.0	1.0	6.0	9.0

¹ Solvent/oil ratios 1:1.

² Wt. percent.

From the results shown in Table II it can be seen that in the purification of each aromatic, the aromatic and solvent ceased to be miscible at a certain, definite water content. Thus, the production of substantially pure aromatics at 77° F. using DADC (dimethyl ammonium dimethyl carbamate) requires at least the minimum concentrations of water shown.

This relationship is shown with clarity in the phase diagrams. In Figure 1, curve 1 outlines the two-phase region to show the raffinate and extract compositions that are obtained by treating a n-heptane-benzene mixture with pure DADC, containing no water. In this instance, the solvent and benzene are completely miscible and point "E" on the curve represents the composition of the extract phase which will give the maximum aromatic concentration. Curve 2 outlines the region of two-phases for DADC containing 2.5% by volume of water. Some increases in selectivity and capacity is noted by the upward shifting of point "E." Curve 3 outlines the two-phase region for a solvent comprising DADC with 5.0% by volume of water. All of the solvent compositions were tested by thoroughly shaking the feed and solvent at 80° F., allowing the mixture to settle and separating the extract and raffinate phases for analysis.

Figure 2 is a phase diagram for the system n-heptane-benzene-solvent at 100° F., where the solvent consists of 88 parts, by weight, of DADC and 12 parts of water. Point "E" again represents the composition of the extract phase which will give the maximum aromatic concentration. However, by using the higher water concentration, a situation is developed which permits the recovery of almost pure aromatics. If point "E" were located close to B (100% solvent), the use of 12% of water would be impractical. However, "E" is at a position such that a high capacity of the solvent for aromatics is obtained. The tests for the results shown in Figure 2 were conducted by the same technique as was used in the tests for Figure 1. In Table III a summary of the analyses for the raffinate and extract phases is shown for the system p-xylene-n-heptane-DADC solvent at 100° F. using the technique just described. The points shown on curve 1 in Figure 4 correspond to the data for "0%" of water in Table III, etc.

5.0	83.6	16.4	0	27.5	72.5	0

Figure 4 reflects the results of Table III as a ternary diagram showing the effect of water dilution of the DADC. Curve 1 is for 0.0% by volume of water, curve 2 for 2.5% by volume of water and curve 3 for 5.0% by volume of water. These results confirm the relationship of the amount of water in the solvent to the extraction temperature and the type of aromatic sought.

The invention will be better understood by reference to Figure 3 wherein is illustrated a process in which the DADC-water solvent is used to extract aromatics from the charge and the solvent is recovered by water extraction of the DADC from the aromatics. Subsequent recovery of the DADC is accomplished by distillation. The process is illustrated by the treatment of a catalytic reformate to obtain a high-purity, benzene-toluene-xylene mixture. Charge reformate is passed through line 1 into extraction tower 2 which is fitted with the usual plates and/or baffles (not shown) to increase the degree of contact. Tower 2 is operated at a temperature of about 80 to 120° F. and a pressure of about atmospheric to 5 p.s.i.g. About 5 to 10 parts of solvent, entering at line 3, are used for each part of charge reformate. Extract leaves tower 2 by line 4, passing to secondary extraction tower 5. Raffinate from tower 2 is passed by line 6 to water-wash tower 7, where it is contacted with water from line 8 at a temperature of about 100 to 120° F. This treatment results in the separation of a paraffinic phase, taken off at line 9, and a water-solvent phase, removed at line 10.

Tower 5, which is constructed like tower 2, receives the extract phase from line 4, and this phase flows countercurrently to the water stream furnished by line 11. This produces a solvent-water mixture which is withdrawn through line 12, and mixed with the solvent-water mixture in line 10 from tower 7, to form a combined stream which flows through line 23 to solvent recovery tower 13. The overhead from tower 5, containing most of the aromatic phase, passes through line 14 to aromatic purification tower 15. The application of heat, as by means of steam coil 16, results in the removal of the last traces of solvent from the extract, the former passing through line 17 to condenser 18 and thence, through recycle line 20, solvent storage 28, and line 3, back to tower 2, or through line 19 back to tower 15 as reflux therein, the latter leaving tower 15 at line 21. A portion of the aromatics recovered in tower 5 is recycled back to tower 2 via line 22 as reflux.

The water-solvent mixture in line 12 joins with that in

line 10 to form a combined stream which flows through line 23 to solvent-recovery tower 13, where it is distilled by heating means 24. The solvent passes overhead via line 25 to condenser 26. Part of the condensed solvent is returned to tower 13 as reflux via line 27; the remainder passes to solvent storage 28 via line 29. The water passes via line 30 to water storage 31 from whence it is recycled to water-washing towers 5 and 7 via lines 32, 8 or 11, or is used to dilute the solvent by passage through line 33 returning to the extraction tower 2. In operating such a system, it has been found that the minimum DADC solvent-to-charge-oil ratio for the extraction of 99.5 percent pure benzene-toluene-xylene mixture in the primary column is 2.5, and the actual solvent-to-charge-oil ratio is 6.8. The corresponding minimum reflux ratio of recycle benzene-toluene-xylene mixture to charge-oil is 1:4 and the actual ratio is 4:7. The optimum solvent-to-oil ratio is governed by the relationships between the feed composition, water content of the solvent, temperature of extraction, and degree of purity desired, but in general solvent-to-oil ratios from about 1:10 to 10:1 are satisfactory.

The process of this invention is applicable to the treatment of any type of hydrocarbon mixture from which economical amounts of aromatics, including benzene and homologues thereof, may be recovered. Such mixtures include products obtained from aromatization reactions. The products obtained from catalytic reforming, hydro-cracking, and dehydrocyclization processes may be used as feed for the present process. Any mixtures containing a paraffinic- or naphthenic type hydrocarbon admixed with benzene, toluene, or the xylenes as simple or complex multi-component mixtures, may be used as the starting material. The charge oil should be liquid at ordinary temperatures and not subject to decomposition at the extraction temperatures or reaction with the selective solvents used herein. One suitable charge oil is the class of products known in the art as catalytic reformates. These liquid products contain a fair concentration of desirable aromatic hydrocarbons. Catalytic reformates are obtained by treating naphthas to reforming, dehydrogenation, hydrocracking and dehydrocyclization reactions at temperatures ranging from 850° F. to about 1000° F. with pressures up to 500 p.s.i.g. in the presence of a metal-containing catalyst.

As a more specific illustration, catalytic reformates obtained as a result of the treatment of a virgin naphtha (B. 175° F.-400° F., API gravity 50° to 60°) with a platinum-alumina catalyst at 875° F. to 975° F. and pressures ranging from 200 to 500 p.s.i.g. may be used. Reformates so produced contain from about 30 to 55 vol. percent of aromatics and constitute a preferred feed for the present process. Reformates produced by reforming a 200°-400° F. virgin naphtha at about 950° F. and 400 p.s.i.g. in the presence of a catalyst comprising about 0.1 wt. percent of platinum on an alumina base are preferred. These formates boil between 100° to 450° F., have an API gravity of 40° to 50° and an aromatic content of 45-55 volume percent. The particular reformate used herein was obtained by subjecting a charge naphtha having a boiling range of 101° F. to 418° F., API gravity 49.2°, RON clear 84.5, RON+0.3 TEL 94.9, 0.02% sulfur, and containing about 56.4 vol. percent of paraffins and naphthenes, 1.2 vol. percent olefins and 42.4 vol. percent aromatics to reforming at about 950° F. to produce a product having an API gravity of 48.8°, I.B.P. 138° F., E.P.B 374° F., RON clear 82.0, RON+3 cc. TEL 93.8 and containing about 54.0 vol. percent paraffins and naphthenes, 1.2 vol. percent olefins and 44.8 vol. percent of aromatics. By precise fractionation and blending to different octane numbers it was determined that this reformate feed material exhibited the following analysis:

¹ Analyzed for benzene content only.

In general, these feed stocks contain a mixture in various proportions of i-butane, n-butane, i-pentane, n-pentane cyclopentane, 2,2-dimethylbutane, 2,3-dimethylbutane, 2-methylpentane, 3-methylpentane, n-hexane, methylcyclopentane, 2-2-dimethylpentane, benzene, 2,4-dimethylpentane, cyclohexane, 2,2,3-trimethylbutane, 3,3-dimethylpentane, 1,1-dimethylcyclopentane, 2,3-dimethylpentane, 2-methylhexane, cis-1,3-dimethylcyclopentane, trans-1,3-dimethylcyclopentane, 3-methylhexane, trans-1,2-dimethylcyclopentane, 3-ethylpentane, n-heptane, 2,2,4-trimethylpentane, cis-1,2-dimethylpentane, methylcyclohexane, ethylcyclopentane other C₈ hydrocarbons, toluene, ethylbenzene, p-xylene, o-xylene and m-xylene which represent the types of hydrocarbon mixtures from which the aromatics, as enumerated, may be separated by the present process. In using reformates as feed hydrocarbons, one purpose is to separate the low-octane compounds so that they may be recycled or otherwise upgraded in octane number, and the high-octane-number products recovered for gasoline blending.

Another type of feed mixture comprises various fractions and mixtures of fractions of reformates which may be used in this invention. For example, a reformate or other source of aromatics may be fractionated to form a benzene concentrate, a toluene concentrate and a xylene concentrate; these may be individually treated or mixed in various proportions and treated to solvent extraction in accordance with this invention to obtain products having a high concentration of the desired aromatic. One such feed material comprises a synthetic mixture of 1 part benzene concentrate, 2 parts toluene concentrate and 1 part xylene concentrate. The purpose of treating such concentrates is to recover aromatics of maximum purity for use as organic intermediates, solvents, etc.

In describing the process, such considerations as rate of flow through the system have been omitted, since they are controlled or limited by the type of extraction tower or system used, i.e., a packed tower, perforated-plate type, or a Scheibel tower. Extraction tower 2 is operated within the general temperature limits of 80° F. to 140° F., or as high as 150° F., from atmospheric pressure to

5 or even 10 p.s.i.g., subject to the provisions of water content of the solvent and/or reflux ratios as specified herein. The solvent-to-feed ratio may vary from 1:10 to 10:1 in tower 2. The purpose of extract recovery tower 5 is to wash a substantial portion of the DADC from the extract phase for which purpose the ratio of water-to-extract phase is adjusted in accordance with known procedures in this art. Water-to-extract ratios of about 0.3:1 to 0.5:1 or higher may be used in tower 5.

In accordance with sound processing techniques, it is advantageous to operate tower 5 and, for that matter, tower 7 at the same temperature and pressure conditions as tower 2. The purpose of tower 7 is to wash the DADC from the raffinate phase using as little water as possible, i.e., water-to-raffinate ratios of .01:1 to as high as .05:1, with .02:1 being optimum. Similarly, the purpose of solvent-recovery tower 13 is to apply enough heat to distill the DADC from the water-wash solutions for which purpose the temperature at the top of the tower will be at least 140° F. and the temperature at the tower bottom will be 212° F. Pressure is used in the system to prevent loss of solvent and maintain the system in the liquid phase. A slight vacuum may be applied to tower 13 to aid the distillation of DADC, which has no tendency to decompose or hydrolyze, and thus adjust its water content. By proper adjustment of the reflux ratio through line 27 and the use of a sufficient number of stages, as is well known in the art, the water content of the distillate DADC may be adjusted to within that range desired for use in tower 2. The water content is determined by following the refractive index of the DADC-water mixture. Final adjustment, or changes therein, is made by addition of water at line 33 or adding fresh solvent to the system. Similarly, in tower 15 the temperature of the partially denuded extract is adjusted so that any remaining DADC and water is removed.

What is claimed is:

1. In the process of separating hydrocarbon mixtures containing aromatic hydrocarbons selected from the group consisting of benzene, toluene, ethyl benzene, and xylenes, and paraffinic hydrocarbons into an extract predominating in said aromatic hydrocarbons and a raffinate predominating in said paraffinic hydrocarbons, the improvement comprising contacting said hydrocarbon mixtures

with a solvent consisting of dimethyl ammonium dimethyl carbamate containing about 3.0 to 25 volume percent of water at a temperature of about 60° to 150° F., separating the composite mixtures into two components 5 consisting of said extract phase and said raffinate phase and recovering said aromatic hydrocarbons substantially free of other hydrocarbons from said extract phase.

2. The process in accordance with claim 1, in which said water is maintained at a concentration of about 3.0 10 to 5.0 volume percent, said temperature is maintained at about 80° to 100° F., and said purified aromatic hydrocarbons are essentially xylenes.

3. The process in accordance with claim 1, in which said water is maintained at a concentration of about 6.5 15 to 10 volume percent, said temperature is maintained at about 77° F., and said purified aromatic hydrocarbon is essentially toluene.

4. The process in accordance with claim 1, in which said water is maintained at a concentration of about 10 20 to 25 volume percent, said temperature is maintained at about 90° to 140° F., and said purified aromatic hydrocarbon is essentially benzene.

5. The process in accordance with claim 1, in which said hydrocarbon mixture comprises a catalytic reformate 25 having a boiling range of about 100° to 450° F., said water is maintained at a concentration of about 15 to 25 volume percent and said temperature is maintained at about 100° to 120° F.

6. The process in accordance with claim 5, in which 30 said temperature is maintained at about 120° F., said water is maintained at a concentration of about 15 to 20 volume percent and the solvent-to-feed ratio is about 2 to 5, with a minimum reflux ratio to feed for the extract phase of about 1 to 4.
